MUSIC ROLL PERFORATOR AND PRINTER,
APPLICATION FILED JUNE 13, 1921.

1,428,277.

Patented Sept. 5, 1922.

2 SHEETS—SHEET 2.

UNITED STATES PATENT OFFICE.

JOSEPH JOHN DAVILLA, OF NEW ORLEANS, LOUISIANA.

MUSIC-ROLL PERFORATOR AND PRINTER.

Application filed June 13, 1921. Serial No. 477,297.

To all whom it may concern:

Be it known that I, JOSEPH J. DAVILLA, a citizen of the United States, residing at New Orleans, in the parish of Orleans and

5 State of Louisiana, have invented certain new and useful Improvements in Music-Roll Perforators and Printers; and I do hereby declare the following to be a full, clear, and exact description of the invention, such as

10 will enable others skilled in the art to which it appertains to make and use the same.

The present invention relates to improvements in perforating and printing mechanism for the paper rolls of player pianos and 15 the like automatic musical instruments, and has for an object to provide an improved machine of this character in which a series of closely assembled punches are made to operate upon the paper-roll or web by the use 20 of electro-magnetic actuating devices controlled from the keyboard of the instrument.

It is another object of the invention to provide a closely assembled grouping of the 25 electro-magnets and of the actuating arms or armatures thereof which connect with the punches and are supported upon a table top of the machine in two groups at opposite sides of the line of the punches.

A further object of the invention lies in 30 providing in conjunction with the improved perforating devices, a printing mechanism involving the use of an endless printing band having desired characters thereon to show the tempo and other directions, and 35 which will move continuously in connection with the band to the end that both perforating and printing operations may be accomplished in the one machine and simultaneously.

40 With these and other objects in view the invention consists in the novel details of construction and combinations of parts more fully hereinafter disclosed and particularly pointed out in the claims.

45 In the accompanying drawings forming a part of this application, and in which similar reference symbols indicate corresponding parts in the several views:

Figure 1 is a plan view with a portion 50 broken away of an improved perforating and printing machine constructed according to the present invention; and

Fig. 2 is a vertical sectional view of the same.

Referring more particularly to the drawings, 1 designates a table supported on a suitable framework including the legs 2. In the central portion of the table is provided an anvil 3 having a central transverse slot 4 therein to receive the punches 55 as hereinafter described.

Openings 5 and 6 are made transversely at opposite sides of the anvil 3 to receive the paper roll or web 7 which is initially wound on a roller 8 at one side of the machine. 60 From the roller 8, the web 7 passes up beneath a guide roller 9 and over a companion guide roller 10 which projects up into the slot 5 and preferably slightly above the upper surface of the anvil 3 in order to 65 suspend the web 7 just above its surface, thus easing its passage thereacross. Similar guide rollers 11 and 12 are provided in and beneath the slot 6 to receive the web 7 in the manner illustrated in Fig. 2. 70

A further pair of guide rollers 13 and 14 are provided respectively beneath the table top 1 at the right side of the machine and in an opening 15 made through the table top. The web is thus carried above a printing platen 16 formed by a portion of the table top and thereafter directed downwardly over a guide roller 17 held on a bracket 18 affixed to the table or a suitable support. The web take-up roll 19 is supported beneath the guide roll 17. 75

Above the anvil 3 are the punches 20 reciprocating vertically in a pair of guides 21 and 22 held spaced apart by blocks 23 and having central vertically alining perforations to receive the several punches 20 and to guide them in a vertically reciprocating movement. 80

End uprights 24 are provided upon the table top at its central portion to receive a beam 25 extending in spaced relation above the upper guide 22 and acting as a stop to limit the upward movement of all of the punches. 85

The beam 25 is considerably wider than 90 the upper guide 22 and extends to opposite sides thereof where it carries two series of screw eyes 26 and 27 having adjusting and lock nuts 28 and 29 to vary the vertical positions of the screw eyes. This is desirable 95 to place the requisite tension upon coil springs 30 and 31, the upper ends of which are carried in the eyes of the members 26

and 27 which connect at their lower ends with the arms or armatures 32 and 33.

The arms 32 extend in one direction or toward one end of the table, while the arms 33 extend in an opposite direction. The free ends of the arms come together near the punches and each punch is provided with a centrally offset portion or boss 34 having a socket 35 in which to receive freely the 10 end of its actuating arm. The arms 32 are pivotally connected, as indicated at 36, to the upper ends of standards 37 erected on the table top.

In a similar manner the other series of 15 arms 33 are pivoted in the upper ends of standards 38 mounted upon the table top at suitable points to receive the same. The arms 32 extend near their pivot points above individual electro-magnets 39, upon the 20 energization of which the armatures are drawn down, with a consequent similar movement of the attached punch 20. A like result is had by the association with the arms 33 of electro-magnets 40.

25 It will be noted more particularly from an inspection of Fig. 1 that the electro-magnets 39 and 40 are disposed in diagonal groups, five such groups being shown at opposite sides of the punches. The groups at one 30 side being arranged in an opposite direction as compared with those at the opposite side of the machine. This arrangement permits the armatures to be located closer together without interference from one another, and 35 permits a closer grouping of the punches 20 so that a more compact machine results.

The punches are arranged as indicated in Fig. 2 in circuits 41 and with individual keys of a keyboard 42. A source of current 43 is included in the circuit and normally open contacts 44 and 45 are adapted to be closed by the keys. In this way a selective closing or vibrating of the electro-magnets is had so that proper controlling 45 perforations may be made in the paper web 7 to reproduce corresponding notes upon the piano.

In Fig. 1 I have shown a pedal perforating mechanism 46 which is a punch of a 50 similar nature also magnetically actuated and which will be understood from the above description.

In conjunction with a perforating mechanism I also provide a printing endless band 55 47 of an over-all length approximately nearly to that of web 7, such band 47 being trained about a pair of rollers 48 and 49 located at one side of the machine and about other rollers 50, 51 and 52 at the opposite 60 side of the machine and upon and about a central roller 53 located beneath the anvil 3.

The roll 52 may be the drive roll and may receive a suitable source of power for this purpose. Both runs of the web 47 extend 65 upwardly at the right-hand side of the ma-

chine, as thus seen in Fig. 2, and the lower run extends initially above a guide roller 54 and subsequently beneath a pressure roller 55 which guides and forces the printing surface of the band against the web as it 70 passes upon the platen 16.

The upper guide roll 56 receives the band 47 from the pressure roll 55, an inking roller 57 preferably being located in conjunction with the roll 56, the band taking the course 75 indicated by the arrow. A similar guide roll 58 is mounted upon the roll 54 and receives the opposite run of the belt. A frame 59 is employed to hold all four of the rollers 54, 55, 56 and 58, and is preferably a 80 skeleton frame mounted in any suitable way upon parts of the table top 1.

As the web 7 moves above the anvil 3, the keyboard 42 is actuated in a well known manner, and as the various keys are depressed, corresponding circuits through the respective magnets 39 and 40 will be closed which will energize these magnets and cause them to attract their respective armatures 32 or 33. When the switch E is closed the 90 master vibrator A is brought into action by current from the battery 43, with the result that the armature B is set to vibrating, making and breaking contact with contact arm C. This action is continuous. When any individual key on keyboard 42 is depressed, and contacts 44 and 45 brought together, then magnets 39 or 40, as the case may be, are energized and consequently draw down their armatures 32 or 33. As long as 95 the individual key in keyboard 42, or number of keys in the keyboard, are depressed, magnets 39 or 40 controlled by the individual keys will continue to pulsate armatures 32 or 33, and will continue this punching 100 until key is released in the keyboard. This pulsation effect in magnets 39 and 40 of armatures 32 and 33 is caused by the making and breaking effect of arm C with vibrator arm B; the whole being actuated by the 110 master vibrator magnet A.

A single vibrator magnet may govern the whole, which is the preferred construction.

The above vibrating current causes a continuous vibration effect of the punches, the 115 punch holes being made to overlap in the web. This produces an elongated slot in accordance with the length of time the piano key is kept depressed.

The punches will be driven downwardly 120 through the web 7 and the slot 4 in the anvil 3 and will thus produce a controlling perforation in the web which will act in conjunction with the tracker of the instrument. The coil springs 30 and 31 initially and 125 normally hold the arms 32 and 33 and associated punches in a raised inoperative position, and this condition continues so long as the magnets remain de-energized.

A suitable tension is put upon the springs 130

30 and 31 by the adjustment of the screw eyes through the nuts 28 and 29. In this way a sharp accurate perforation is made by a quickly responsive punch. The pedal 5 punch 46 is also actuated in the well known way from the foot pedal of the instrument.

As the web 7 is fed to the take-up roll 19 it passes above the platen 16 and the pressure roll 55 is so situated with respect to 10 the platen that a driving relation is established between these two parts. Otherwise, if desirable, the web and the band 47 may be independently moved. In any event the band will move into printing engagement 15 with the web 7 and will reproduce thereupon various directions as to the tempo and expression.

There is also provided a word perforator 70 adapted to operate upon the web near one 20 edge thereof. It is not actuated by the keyboard but is independent of all the other punches. This acts as a push button placed at a convenient part of the piano, say, for instance, on the right arm, so that when a 25 master roll is being perforated in order to establish the proper position for the inserting of words by the printing belt, a singer will push this button as he forms each word syllable, and in this way perforations are 30 made at extreme side of the roll which do not come within the scope of the tracker.

When the music roll is complete it will therefore have perforations in one margin to indicate the proper position for the inserting 35 of words. Then the printing belt is provided with rubber words cemented thereon, which words are brought into printing relation to the web in accordance with the perforations.

40 The pedal perforator 46 at the opposite side of the machine is for purposes of tone expression and is operated by the pedal of the piano.

It will be appreciated from the foregoing 45 that I have provided an exceedingly compact perforating and printing mechanism for player piano rolls and the like in which the punches and their individual actuating devices are associated compactly and grouped 50 close together so as to form a comparatively small machine to accommodate a printing mechanism which is mounted partially beneath the framework of the perforated machine and necessitates only few and simple 55 parts above the paper web at a single point.

It is obvious that those skilled in the art 60 may vary the details of construction and arrangements of parts without departing from the spirit of my invention, and therefore

I do not wish to be limited to such features except as may be required by the claims.

I claim:

1. A music roll perforator and printer comprising a table having slots therein with a portion forming an anvil between the 65 slots, selectively-controlled punches above the anvil for perforating the web, means beneath the table for supporting the web and guiding it upon the upper surface of the anvil through one of the slots and subsequently 70 downwardly through the other slot at the opposite side of the anvil, said table having a further slotted portion forming a platen, and means for guiding the web upon the platen, substantially as described. 75

2. A music roll perforator and printer comprising a table having slots therein and an anvil between the slots, selectively-controlled punches for perforating the web when upon the anvil, means to initially carry 80 the web beneath the table at one side, guide rollers situated at the slots for directing the web upon the anvil and for returning it beneath the table, said table having an end portion providing a platen with a slot leading 85 to the upper surface thereof, and guide rollers for receiving the web and directing it upon the platen, substantially as described.

3. A music roll perforator and printer 90 comprising a table having slots and an anvil between the slots, punches above the anvil, electro-magnetic means for actuating the punches situated on the table at opposite sides of the slots, and means to guide a web 95 upwardly upon the anvil and thence down beneath the table after being perforated by the punches, said table having a portion at one end thereof appropriated to form a platen, adapted to receive the web after its 100 passage across the anvil, substantially as described.

4. A music roll perforator and printer comprising a table, supporting legs therefor, two series of electro-magnets supported 105 upon opposite sides of the table center, said table center providing an anvil with slots to either side thereof and a central slot, punch holding and guiding means above the anvil, punches movably held therein in normally and yieldably raised position and connected for actuation to said electro-magnets whereby to perforate a web, means for guiding a web beneath the table up through one slot across the anvil and down through the 110 other slot, said table having an end portion forming a platen with a slot at one side thereof, and means for guiding the web through said last slot upon the plate, substantially as described. 115

JOSEPH JOHN DAVILLA.
